APPARATUS FOR SEQUENTIALLY COMPRESSING RESILIENT ARTICLES

Robert L. Surina, Westmont, Ill., assignor to Western Electric Company, Incorporated, New York, N.Y., a corporation of New York

Filed Apr. 9, 1962, Ser. No. 186,031
8 Claims. (Cl. 100—215)

The present invention relates generally to apparatus for sequentially compressing resilient articles, and more particularly to apparatus for loading and compressing resilient articles in a rack by stages. Accordingly, the general objects of the invention are to provide new and improved apparatus of such character.

It is often required that resilient articles be compressed to some thickness less than the original thickness. In the past, this has been accomplished by compressing each article individually or inserting a large quantity of such articles into a container and compressing them in mass, all at once. Both procedures have their shortcomings, for to compress each article individually is time consuming and inefficient. Yet, to compress them in mass results in a nonuniform distribution of the pressure exerted to compress the articles and consequently non-uniform compressed thicknesses of the articles.

Accordingly, other objects of the invention are to provide new and improved apparatus for loading and compressing resilient articles in a rack by stages, wherein the articles are alternately inserted and compressed in groups several articles thick so that the pressure exerted to compress the articles is uniformly distributed, resulting in uniform compressed thicknesses of the articles.

In the specific field of manufacturing certain capacitors, a wide sheet of metallized Mylar is wound into a long cylindrical capacitor roll, where the Mylar serves as a dielectric between adjacent metal layers. These rolls are cut into several capacitor bodies of a desired length which must be compressed with spacer plates at a particular pressure to form spacer-separated flat capacitor bodies and loaded into U-shaped racks so that the capacitor bodies are aligned in columns and layers with their ends exposed for subsequent solder-capping and lead-attaching operations. It is requisite that the pressure exerted to compress the capacitor bodies be uniformly distributed so that all of the capacitors are compressed to the same thickness.

Therefore, further objects of the invention are to provide new and improved apparatus for loading and compressing spacer-separated resilient capacitor bodies in a rack by stages so that the pressure exerted to compress the capacitor bodies is uniformly distributed to all of them and further, so that the capacitor bodies are inserted in the rack in layers and in columns which are uniformly aligned.

With the foregoing and other objects in mind, apparatus in accordance with certain aspects of the invention includes a holder defining a chamber into which articles are inserted in groups which are several articles thick. Each succeeding group, after the first, is inserted against the outer surface of the preceding group after the preceding group has been compressed. A reciprocable mechanism is provided for compressing each group in turn to a lesser thickness, the first group being compressed against a base surface of the chamber and the succeeding groups respectively against the outer surface of the preceding compressed group. Mechanism is provided for engaging and holding the outer surface of each compressed group after the compression operation and before the retraction of the compressing mechanism to maintain the compressed state of the previously compressed articles.

According to certain more specific aspects of the in-

2

vention, the engaging and holding mechanism includes a plurality of fingers spaced to engage and hold the outer surface of the compressed groups. A mechanism is provided for moving the fingers into and out of the chamber and lengthwise thereof so that they are moved into engagement with the outer surface of each compressed group in turn. In addition, the holder constitutes a U-shaped rack, and a rectangular frame is provided for holding the rack vertically erect. A mechanism having a plurality of equally spaced fingers is provided for defining openings into which articles are inserted to form a layer in the rack so that the articles of successive layers are uniformly aligned in columns. This function is facilitated by mounting the fingered mechanism on the upright frame for vertical movement relative thereto and for horizontal movement into and out of the rack.

Other objects, advantages, and aspects of the invention will appear from the following detailed description of a specific embodiment thereof, when taken in conjunction with the appended drawings, in which:

FIG. 1 is a perspective view of an apparatus forming a preferred embodiment of the invention;

FIG. 2 is a front view of the apparatus with several articles inserted in layers in the rack;

FIG. 3 is an enlarged sectional view taken generally along the line 3—3 in FIG. 2, specifically showing the tray and the engaging and holding mechanism;

FIG. 4 is a sectional view of the tray taken generally along the line 4—4 in FIG. 3;

FIG. 5 is a sectional view of the engaging and holding mechanism taken generally along the line 5—5 in FIG. 3;

FIG. 6 is a sectional drawing of the engaging and holding mechanism shown in FIG. 5, but with the fingers and the pawl in a retracted position; and

FIG. 7 is a schematic diagram of the control circuit for actuating the pneumatic cylinder.

Referring now in detail to the drawings and particularly to FIGS. 1 and 2, an apparatus in accordance with a preferred embodiment of the invention is utilized to load and compress capacitor bodies in spacer-separated layers by stages. Generally, the spacer-separated layers of capacitor bodies, including the spacers, constitute the "resilient articles" to be compressed and typify the use of the invention; however, various different types of articles, composite or uniform, may be compressed equally well using the apparatus of the invention. The apparatus includes a rectangular frame 10 defining an opening 11 into which a U-shaped rack 12 is inserted, the bottom thereof being channeled to receive a pair of stops 13—13 mounted on a base plate 14 of the frame 10. The rack 12 is secured in the frame 10 by a pair of clamps 15—15 which are lowered so that they overlie the upper edges of the rack 12. Capacitor bodies 16—16 to be inserted into the rack 12 are placed in mass into a tray 17 so that an operator can insert them into the rack to form a layer with simple and efficient hand-movements of a limited distance each.

To aid in this function, the tray 17 is mounted from the front of the frame 10 for vertical movement on a pair of fixed guide rods 18—18 slidably received in associated bushings 19—19 on the tray 17, as shown in FIGS. 3 and 4. In addition, a slide 21 is mounted beneath the tray 17 in a pair of guides 22—22, as shown in FIGS. 2 and 4, for horizontal movement into and out of the rack 12, the slide 21 having equally spaced fingers 23—23 defining openings 24—24 into which the capacitor bodies 16—16 are inserted when the slide is advanced to the position shown in FIGS. 3 and 4. All of the above-mentioned movements of the tray 17 and the slide 21, both dependent and independent, are accomplished by elevating or lowering and pushing or pulling a handle 26 depending from the slide.

Initially, the operator positions the tray 17 near the bottom of the frame 10 and advances the fingers 23-23 of the slide 21 with the handle 26 so that the fingers 23-23 overlie and rest on a thick spacer plate 27 (FIG. 2) inserted at the bottom of the rack 12. Capacitor bodies 16-16 from the tray 17 are then inserted between the fingers 23-23 to form a layer in the rack and a thin spacer plate 28 is placed on top of the layer. The tray 17 is subsequently repositioned at the proper height for the succeeding layers by (1) withdrawing the slide 21 from within the rack 12, (2) elevating the tray 17 to a position above the layer just inserted, (3) advancing the slide into the rack again so that the fingers 23-23 overlie the spacer plate 28, and (4) lowering the tray so that the fingers rest on the spacer plate. Capacitor bodies 16-16 are then inserted between the fingers 23-23 again and the operation repeated until a selected number of layers separated by thin spacer plates 28-28 have been inserted into the rack 12.

When the selected number of layers, as for example fifteen, has been inserted in the rack 12, a thick spacer plate 27 is placed on top of the pile-up of layers and a pneumatic cylinder 29 is actuated to extend a ram 31 so as to engage the thick spacer plate 27 and compress the pile-up of layers therebeneath against the bottom spacer plate 27 under a predetermined amount of pressure. The selection of the number of layers to be compressed at one time is not arbitrary, for the number must be great enough to insure a high degree of efficiency, but not so great as to preclude uniform pressure distribution among the capacitor bodies 16-16 in any one particular layer and also among each of the various layers. In this particular example, fifteen layers is the selected number because this is the optimum number of layers that can be compressed at one time and still result in uniform distribution of the pressure among the various layers. In addition, the thick spacer plate 27 is provided in this specific example to insure that the pressure will be uniformly distributed among all of the capacitors in any one layer.

After a pile-up of fifteen such layers has been compressed, a carriage 32 mounted at the rear of the frame 10 (FIGS. 1, 3, 5 and 6) is lowered on a pair of guide rods 33-33 slidably received in a pair of bushings 34-34 so that a pair of fingers 36-36 can be inserted through vertically elongated slots 37-37 in a back plate 37' to a position within the rack 12 where they overlie the compressed pile-up. The insertion of the fingers 36-36 is initiated by a pair of handles 38-38 pivotably mounted to the carriage by pins 39-39 so that they extend toward the front of the frame 10, one from either side thereof.

Movement of the handles 38-38 from the position shown in FIG. 3 in the direction indicated by the arrows X-X is transmitted through pins 41-41, slidably received in grooves 42-42 of the handles, to a slide 43, causing it to move forward relative to the carriage 32 in the direction indicated by the arrow Y. The fingers 36-36 are mounted at the forward edge of the slide 43 and are of such length that they overlie the compressed pile-up, as illustrated in FIG. 5, when the handles 38-38 have been actuated to move the slide 43 forward.

This same movement is transmitted to a pawl 44, slidably mounted on the carriage 32, through a lost-motion coupling 46 to engage the pawl 44 with the teeth 47 on a toothed rack 48 vertically disposed at the rear of the back plate 37' as shown in FIG. 5. The lost-motion coupling 46 includes a pin 49 projecting downward from the pawl 44, which pin 49 is slidably received first through a slot 52 in a portion 53 of the carriage 32 separating the pawl 44 from the slide 43, and then in a slot 54 in the slide 43. The length of the first slot 52 is calculated to limit the movement of the pin 49 to just that amount necessary to engage and disengage the pawl 44 with the teeth 47-47 of the rack 48. On the other hand, the second slot 54 is of such length as to allow the

slide 43 to fully withdraw the fingers 36-36 from over the pile-up before the front edge of the slot 54 engages the pin 49 to disengage the pawl 44 from the rack 48 (FIG. 6), the pin 49 being constantly biased toward the front edge of the first slot 52 by a spring 56.

Thus, by spreading the handles 38-38 apart, the slide 43 is moved forward (1) to extend the fingers 36-36 so that they overlie the pile-up and (2) to move the pawl 44 into engagement with the rack 48 to lock the carriage 32 against elevational movement by permitting the spring 56 to bias the pin 49 against the front edge of the first slot 52 (FIG. 5). With the fingers 36-36 so extended, the rear edge of the second slot 54 does not engage the pin 49, but instead is coextensive with the rear edge of the first slot 52 so that the pawl 44 is free to ratchet over the teeth 47-47 of the rack 48 against the bias of the spring 56 when the carriage 32 is lowered to engage and hold down the compressed pile-up with the fingers 36-36.

The pneumatic cylinder 29 is then actuated to retract the ram 31 so that another group of fifteen layers of un-compressed capacitor bodies 16-16 may be inserted into the rack 12, after which the pneumatic cylinder 29 is again actuated to compress the newly inserted layers against the thick spacer plate 27 on the upper layer of the pile-up held in a compressed state by the fingers 36-36. With the newly inserted layers so compressed, the handles 38-38 are pulled forward so as to retract the slide 43 to withdraw the fingers 36-36 from over the pile-up and disengage the pawl 44 from the rack 48. The carriage 32 is then elevated by pulling up on the handles 38-38 to a position where the fingers 36-36 may again be extended so as to overlie the newly compressed pile-up of layers, after which the carriage 32 is lowered so that the fingers 36-36 engage and hold down the upper layer of the compressed pile-up, the pawl 44 locking the carriage 32 against elevational movement as before.

These operations of alternately loading and then compressing capacitor bodies 16-16 in the rack 12 by stages are continued until the rack has been filled to capacity, at which time it is capped and removed from the frame 10 for subsequent operations. If for some reason it is desired to suspend the tray 17 in a position above the normal rest position on top of the uppermost layer of capacitor bodies 16-16, a locking mechanism 57 is provided for just that purpose. The locking mechanism 57 includes a lever 58 pivotally mounted at the right side of the tray 17, as viewed in FIGS. 1 and 2, which is provided with an oversize bore 59 through which one of the guide rods 18 passes so that the peripheral edges of the bore 59 engage and hold fast to the guide rod 18 when the lever 58 is pivoted downward at its remote end 61. The locking mechanism 57 is released again by raising the remote end 61 of the lever 58 to disengage the peripheral edges of the bore 59.

Operation

After a U-shaped rack 12 has been inserted and clamped within the rectangular frame 10, the operation of this device is commenced by first lowering the tray 17, filled with capacitor bodies 16-16, and inserting the fingers 23-23 into the rack 12 so that they overlie and rest on a thick spacer plate 27 inserted at the bottom thereof. Capacitor bodies 16-16 are then inserted in the openings 24-24 defined by the fingers 23-23 to form a layer and a thin spacer plate 28 is placed on top of the layer. The tray 17 is subsequently repositioned at the proper height for the succeeding layer by (1) withdrawing the slide 21 from within the rack 12, (2) elevating the tray 17 to a position above the layer just inserted, (3) advancing the slide into the rack again so that the fingers 23-23 overlie the spacer plate 28, and (4) lowering the tray so that the fingers rest on the spacer plate 28. Capacitor bodies 16-16 are then inserted

between the fingers 23—23 again, and the operation repeated until fifteen such layers separated by thin spacer plates 28—28 have been inserted into the rack 12.

After fifteen such layers have been inserted, a thick spacer plate 27 is placed on top of the pile-up and the operator presses two push-button switches 62 and 63, one with each hand, to actuate the pneumatic cylinder 29 to compress the pile-up. The requirement that the operator press both push-button switches 62 and 63 is provided as a built-in safety feature, and he must hold these buttons down until the ram 31 exerts a predetermined amount of pressure in compressing the pile-up of layers as an additional safety measure.

These safety features are incorporated as part of the electrical circuit shown in FIG. 7 for actuating the pneumatic cylinder 29. Before the push-button switches 62 and 63 are pressed, the switches complete a circuit to a first control relay 64 which locks itself in an energized state by closing a contact 66 to by-pass the switches 62 and 63. When the two push-button switches 62 and 63 are pressed, normally open contacts 67 and 68 respectively associated therewith are closed (the energization of the relay 64 having already closed a contact 69) to complete a circuit to a solenoid valve 71. The operator must hold the switches 62 and 63 down to maintain the completed circuit to the solenoid valve 71 until the ram 31 exerts a predetermined amount of pressure on the pile-up, at which time a pressure-sensitive diaphragm 72 closes a switch 73 to complete a circuit (in combination with a contact 74 which was also closed by the energization of the control relay 64) to a second control relay 76. Energization of the second control relay 76 closes a locking contact 77 and a contact 78, the closing of the latter enabling the operator to discontinue holding down the switches 62 and 63 without causing an open circuit to the solenoid 71 since the contact 78 parallels the switch contacts 67 and 68.

With the ram 31 still extended and holding the pile-up in a compressed state, the fingers 36—36 are extended to overlie the pile-up and the pawl 44 is engaged with the toothed rack 48, after which the carriage 32 is lowered until the fingers 36—36 engage the thick spacer plate 27, the pawl 44 locking the carriage 32 against elevational movement to hold the pile-up in a compressed state. The ram 31 is retracted in the pneumatic cylinder 29 by pressing a push-button switch 79 to open a normally closed contact 81, thereby deenergizing the solenoid valve 71 and enabling a spring (not shown) to reverse the solenoid valve 71. The pressing of the push-button switch 79 also deenergizes the control relays 64 and 76 and thereby causes the contacts associated therewith to return to their initial positions.

The tray 17 is then repositioned and the fingers 23—23 extended for the insertion of the next layer of capacitor bodies 16—16 on top of the thick spacer plate 27. The capacitor-body inserting operations are then repeated until another group of fifteen layers has been inserted and the pneumatic cylinder 29 is again actuated to compress the newly inserted layers against the upper layer of the previously compressed pile-up. With the newly inserted layer so compressed, the fingers 36—36 are withdrawn from the pile-up and the pawl 44 is disengaged from the rack 48 by the handles 38—38. The carriage 32 is then elevated to a position above the newly compressed pile-up where the fingers 36—36 are again extended and the pawl 44 engaged, after which the carriage 32 is lowered to engage and hold down the upper layer of the composite, compressed pile-up.

These operations of alternately loading and then compressing capacitor bodies 16—16 in the U-shaped rack 12 by stages is continued until the rack has been filled to capacity, at which time it is capped and removed from the frame 10 for subsequent operations.

While one specific embodiment of the invention has been described in detail hereinabove, it will be obvious

that various modifications may be made without departing from the spirit and scope of the invention.

What is claimed is:

1. Apparatus for sequentially compressing resilient articles, which comprises:

a holder defining a chamber into which the articles to be compressed may be inserted in a succession of loosely stacked groups with each succeeding group after the first being placed against an outer surface of the preceding group after the preceding group has been compressed;

reciprocable means for compressing each group of articles in turn to a lesser thickness, the first group being compressed against a base surface of the chamber, and the succeeding groups respectively against the outer surface of the preceding group;

means for engaging and holding the outer surface of the compressed group after each compression operation to maintain the compressed state of the previously compressed articles; and

means for moving said engaging and holding means into and out of the chamber and along said holder, so that said engaging and holding means may be moved into engagement with the outer surface of each compressed group in turn after the compression operation and before the retraction of said compressing means.

2. Apparatus for sequentially compressing resilient articles, which comprises:

a holder defining a chamber into which the articles to be compressed may be inserted in a succession of loosely stacked groups which are several articles thick with each succeeding group after the first being placed against the outer surface of the preceding group after the preceding group has been compressed;

reciprocable means for compressing each group of articles in turn to a lesser thickness, the first group being compressed against a base surface of the chamber, and the succeeding groups respectively against the outer surface of the preceding group;

a plurality of fingers spaced to engage and to hold the outer surface of each compressed group in turn after the compression operation and before the retraction of said compressing means, to maintain the compressed state of the previously compressed articles; and

means for moving said fingers into and out of the chamber and along said holder, so that said fingers may be moved into engagement with the outer surface of each compressed group in turn regardless of the total number of compressed groups, the chamber being slotted to permit the recited movements of said fingers.

3. Apparatus for loading and compressing resilient articles in a rack by stages, which comprises:

a frame for receiving and holding the rack so that articles may be inserted therein in groups of loosely stacked layers with each group succeeding the first being placed against the outer layer of the preceding group after the preceding group has been compressed; reciprocable means for compressing each group in turn to a lesser thickness, the first group being compressed against the base surface of the rack and the succeeding groups respectively against the outer layer of the preceding group;

means for engaging and holding the outer layer of the compressed group after each compression operation to maintain the compressed state of the previously compressed articles; and

means for moving said engaging and holding means into and out of the rack and lengthwise of said frame, so that said engaging and holding means may be moved into engagement with the outer layer of each compressed group in turn after the compression op-

- eration and before the retraction of said compressing means.
4. Apparatus for loading and compressing resilient articles in a U-shaped rack by stages, which comprises: an upright, rectangular frame for receiving and holding the rack vertically erect with the open sides thereof exposed so that articles may be inserted therein in groups of spacer-separated layers with each group succeeding the first being placed on top of the preceding group after the preceding group has been compressed; 5 reciprocal means for compressing each group in turn to a lesser thickness, the first group being compressed against the bottom of the rack and the succeeding groups respectively against the uppermost layer of the preceding group; 10 means for engaging and holding down the uppermost layer of the compressed pile-up after each compressing operation to maintain the compressed state of the previously compressed articles; and 15 means for moving said engaging and holding means into and out of the rack and vertically along said frame, so that said engaging and holding means may be moved into engagement with the uppermost layer of the pile-up after each compressing operation to hold the pile-up in the compressed state while (1) said compressing means is retracted, (2) a new group of uncompressed layers is inserted, and (3) said compressing means is again actuated to compress the newly inserted uncompressed group. 20
5. The apparatus as recited in claim 4, wherein the engaging and holding means comprises: a carriage slidably mounted on the upright frame for vertical movement; and 25 extendable fingers slidably mounted horizontally on said carriage such that they overlie the pile-up of layers, through an open side of the U-shaped rack, in an extended position, but not in a retracted position, said carriage being so positionable with said fingers extended that said fingers engage and hold down the uppermost layer of each succeeding group in turn after it has been compressed; and 30 wherein the moving means for the holding and engaging means includes: releasable means for locking said carriage against elevational movement relative to the frame when said fingers overlie and are engaged with the uppermost layer of the compressed pile-up so that the pile-up is held in the compressed state, said locking means being released after a new group has been inserted and compressed to facilitate adjustment of said fingers and said carriage to hold down the uppermost layer of the newly compressed group. 35
6. The apparatus as recited in claim 4, wherein the engaging and holding means and the moving means therefor comprise: a toothed rack vertically mounted on the upright frame; a carriage mounted on the upright frame for vertical sliding movement; 40

- 8
- a spring-biased pawl slidably mounted on said carriage for releasable engagement with the teeth on said toothed rack, said pawl locking said carriage against elevational movement when engaged with said toothed rack; extendable fingers slidably mounted horizontally on said carriage such that they overlie the pile-up of layers through an open side of the U-shaped rack, in an extended position, but not in a retracted position; and reciprocal means for simultaneously extending said fingers and engaging said pawl with said toothed rack so that said fingers engage and hold down the uppermost layer of the compressed pile-up, and for simultaneously retracting said fingers and disengaging said pawl, after a new group has been inserted and compressed, so that said carriage can be elevated to a position where said fingers can be extended and said pawl engaged to hold down the new uppermost layer of the compressed pile-up.
7. The apparatus as recited in claim 4, wherein: means are provided, including a plurality of equally spaced fingers, for defining openings into which articles are inserted to form a layer in the rack so that the articles of successive layers are uniformly aligned in columns; and means are provided for mounting said fingered means on the upright frame for vertical movement relative thereto and for horizontal movement into and out of the rack.
8. The apparatus as recited in claim 4, wherein: a tray is slidably mounted on said upright frame for vertical movement, said tray being designed to hold articles to be inserted in the U-shaped rack so that they are readily accessible for such insertion; and a slide having a plurality of equally spaced fingers is mounted from said tray so that the fingers thereon can be extended into and retracted from the U-shaped rack through an open side thereof, the fingers being spaced apart such that articles can be inserted therebetween to form a layer when extended into the rack, said tray initially being positioned with the fingers extended and resting on the bottom of the rack for the insertion of the first layer, and is repositioned at the proper height for subsequent layers by (1) withdrawing the fingers, (2) elevating said tray, (3) extending the fingers again, and (4) lowering said tray so that the fingers rest on the layer just inserted.
